BLOCK AND WALL CONSTRUCTION

Filed May 28, 1930

INVENTOR.
Stanley Brozek,
BY Jerry A. Mathews

ATTORNEY.

UNITED STATES PATENT OFFICE

STANLEY BROZEK, OF DETROIT, MICHIGAN

BLOCK AND WALL CONSTRUCTION

Application filed May 28, 1930. Serial No. 456,406.

My invention relates to a building block and to a wall construction embodying the same.

In some locations, building regulations require that the foundation wall be formed of solid blocks, brick, or concrete. My invention provides a solid block meeting these requirements.

In accordance with my invention, a solid block is provided which is adapted to be used in connection with a brick facing, in a manner to properly bond the brick facing to the same. In addition to this, adjacent layers of blocks may have interlocking engagement. A solid block of this character is heavy and difficult to handle. To meet this condition, I provide vertical hand receiving grooves or slots, which extend through the top and bottom of the block. At one end, these slots pass through the vertical and horizontal walls of the brick receiving recess formed in the block. Hand holes or recesses are formed in the block at its ends, beneath the brick receiving recess, and are in free communication with the hand receiving grooves. The hand receiving grooves are of sufficient size to receive the entire hand, whereby the blocks may be properly manipulated, when inverted, as well as when the brick receiving recess is in the upper position. When inverted, the blocks will have interlocking engagement. When the brick receiving recesses are arranged uppermost, the hand may be inserted therein, in whole or in part, effecting a more convenient manipulation of the block. The present invention is an improvement upon the block shown in my Patent No. 1,753,820, issued April 8, 1930.

In the accompanying drawings, forming a part of this specification, and in which like numerals are employed to designate like parts throughout the same,

Figure 1 is an end elevation of a wall embodying my invention,

Figure 2 is a perspective view of one of the blocks,

Figure 3 is a plan view of the same,

Figure 4 is a vertical section taken on line 4-4 of Figure 3, and,

Figure 5 is a horizontal section taken on line 5-5 of Figure 4.

In the drawings, wherein for the purpose of illustration, is shown a preferred embodiment of my invention, the numeral 10 designates a solid block formed of concrete, clay or other plastic material. This block has a height equal to the combined height of a plurality of bricks plus the mortar joints, such as three bricks, and has a width equal to the combined width of two bricks, plus the mortar joints. The block may be formed in any suitable lengths, such as the combined lengths of two bricks, plus the mortar joints. The block is provided upon one corner, such as the upper corner, with a brick receiving recess 11, extending throughout the entire length of the same, and passing through the ends thereof. This recess preferably has a width of about one-half of the width of the block.

The block 10 is provided at its opposite ends, with substantially vertical hand receiving grooves or slots 12, sufficiently large to completely receive the hands. These grooves extend through the top and bottom of the block, and also pass through the vertical and horizontal walls of the brick receiving recess. The block is provided in its ends with horizontal finger holes 13, arranged near and beneath the brick receiving recess and in free communication with the hand receiving grooves 12.

In Figure 1, a wall construction is shown embodying horizontal layers 14, 15, 16 and 17 of the blocks 10. The blocks 10 in the layer 17 have their brick receiving recesses arranged remote from the brick facing 18, while the blocks in the layer 16 are inverted so that the extension 19 of the same projects into the brick receiving recess 11 of the blocks in the layer 17, while the extension 19 of the blocks in the layer 17 project into the brick receiving recesses of the blocks in the layers 16, these blocks thereby interlocking. The blocks in the layer 15 have their flat bottoms arranged upon the flat inverted bottom of the blocks in the layer 16 and their brick receiving recesses face inwardly toward the brick facing 18. The blocks in the layer 14

have their flat bottoms arranged adjacent to the blocks in the layer 15, while the brick receiving recesses face outwardly with respect to the brick facing, to receive the extensions 16 of the blocks, in the next layer, which would be inverted.

The brick facing 18 embodies horizontal layers of bricks 20 and 21. The bricks in the layer 20 extend longitudinally of the wall, 10 while the bricks in the layer 21 are disposed transversely to enter the brick receiving recesses 11 and bond with the blocks in the layer 15.

In view of the foregoing description, it 15 is obvious that the blocks may be conveniently handled by the mason, inserting the hands in the grooves 12 and the finger holes 13 and this will permit the blocks to be shifted to close end to end relation without 20 the hands scraping upon the adjacent block. When the brick receiving recess is arranged uppermost, the hand may be inserted in whole or in part, within this recess, which aids in the convenient manipulation of the block. 25 Further, when the block is inverted, the hand may be inserted into the hand receiving groove, so that the fingers may engage with in the finger holes 13.

While I have shown the solid blocks as associated with a brick facing, yet the invention is not restricted to the use of the brick facing, as a solid wall may be formed entirely of the solid blocks, the blocks in each two layers being inverted with respect to 35 each other, so that the extension of one block enters the recess of the other block. In handling the blocks, whether they are used with the brick facing or not, the arrangement of the vertical grooves and hand holes 40 renders it possible for the mason to properly engage and handle the block in the upright or the inverted position.

It is to be understood that the form of my invention, herewith shown and described, 45 is to be taken as a preferred example of the same, and that various changes in the shape, size and arrangement of parts, may be resorted to, without departing from the spirit of my invention, or the scope of the subjoined claims.

Having thus described my invention, I claim:—

1. A solid block for building a wall having a brick facing, said block having a height approximating the combined height of a plurality of bricks, said block being provided upon one corner with a brick receiving recess extending throughout its entire length and being approximately one-half of the width of 55 the block, and having a depth approximately equal to the height of the brick, said block being provided in its ends with vertical hand receiving grooves which extend through the top and bottom of the block, said grooves 60 passing through the vertical and horizontal 65

walls of the brick receiving recess and leading into the ends of said recess, the ends of the block having finger holes arranged near the brick receiving recess and leading into the vertical grooves, the arrangement being such that the hands may be passed through either end of the vertical hand receiving grooves and the hands inserted in part or in whole within the brick receiving recess when it is arranged uppermost so that the fingers 70 may be conveniently introduced into said finger holes. 75

2. A wall construction comprising a plurality of horizontal layers of solid blocks, each block having a brick receiving recess at one corner extending throughout its entire length, each block being provided at its ends with vertical hand receiving grooves extending through its top and bottom, each block being further provided with finger holes arranged adjacent to the brick receiving recess and leading into the hand receiving grooves, the blocks in the adjacent layers being inverted with respect to each other so that the extension of one block enters the brick receiving recess of the other block, the blocks in the next layer having their brick receiving recesses arranged uppermost, and a brick facing for the blocks comprising layers of bricks extending longitudinally of the blocks and a layer of transversely arranged bricks for entering the recess of the blocks in the last named layer. 85 90 95

3. A solid block for building a wall, said block being provided upon one corner with a recess extending throughout its entire length forming a projection upon the block, said block being provided in its ends with substantially vertical hand receiving grooves which extend through the top and bottom of the block, said grooves passing through the vertical and horizontal walls of the recess and leading into the ends of said recess, the ends of the block having finger holes arranged near the brick receiving recess and leading into vertical grooves, the arrangement being such that the block may be inverted so that the extension of one block will enter the recess of the adjacent block and the hands may be passed through either end of the vertical 100 105 110 115 120 125 130

In testimony whereof I affix my signature.
STANLEY BROZEK.
